SHUTTLE-ACTION FOR LOOMS.

1,322,857.

Specification of Letters Patent. Patented Nov. 25, 1919.

Application filed October 29, 1917. Serial No. 199,168.

To all whom it may concern:

Be it known that we, JOZEF WOJTASIEWICZ and JOHN ZAJAC, citizens of Austria, residing at Chadwicks, in the county of 5 Oneida and State of New York, have invented certain new and useful Improvements in Shuttle-Actions for Looms, of which the following is a specification, reference being had therein to the accompanying drawing.

10 Our invention relates to a shuttle action for looms and we declare the following to be a full, clear, concise and exact description thereof sufficient to enable anyone skilled in the art to which it appertains to make 15 and use the same reference being had to the accompanying drawings in which like reference characters refer to like parts throughout the specification.

The object of the invention is to provide 20 a durable device for throwing the shuttle across the loom in the usual manner of weaving. In the construction of looms, heretofore, the mechanism for throwing the shuttle across the loom was under so great 25 a strain that the parts in connection therewith wore out very quickly, thereby necessitating new ones. This invention is designed to overcome that serious defect by 30 transferring the strain to levers that are moved alternately, whereby to effect the actuation of the shuttle.

The object will be understood by referring to the drawings in which:

Figure 1 is a perspective view of the 35 framework of a loom, showing the shuttle actuating device attached thereto;

Fig. 2 is an enlarged perspective view of a portion of the lay of the loom, showing parts of the novel mechanism employed;

Fig. 3 is a perspective view of a shaft employed on the loom for rocking the lay;

Fig. 4 is a detail perspective view of a shuttle box employed;

Fig. 5 is a detail perspective view of the 45 end of a movable member employed;

Fig. 6 is an end elevation of the loom frame and shuttle actuating device;

Fig. 7 is an enlarged view showing a vertical section of a portion of the lay of the loom and parts of the shuttle actuating device in elevation;

Fig. 8 is a perspective view, enlarged, of the portion of the lay shown in Fig. 7 and of the shuttle actuating device.

Referring more particularly to the drawings, the frame of the loom is represented by —1— and the lay by 2. The lay 2 is supported by the adjustable swords 3 and 4 which are fulcrumed upon the rod 5 having bearings in the cross beams 6—6 of the frame —1—, whereby the lay 2 is allowed a rocking motion, as is well known in the construction of looms. The swords 3 and 4 are split and shouldered at 70 and provided with a plurality of holes for the insertion of bolts, whereby they may be adjusted as to length.

The mechanism for rocking the lay 2 embodies the crank shaft 7 that has bearings in the cross bars 8—8 of the frame —1—. 70 The crank shaft 7 is formed with the —U— shaped offsets 9—9. Arms 10—10 are pivoted to the swords 3 and 4 and to the offsets 9, whereby to connect the lay 2 with the crank shaft 7. A spur gear 11 is mounted 75 to turn with the shaft 7 and is in mesh with the spur gear 12 mounted to turn with the rock shaft 13 which carries a pulley 14 that is connected by a belt to the power supply, not shown.

The lay 2, comprises the member 15 having on the one end 16 the side flanges 17 and 18. The flange 18 is higher than the flange 17 and has attached to it a strip or stay piece 19 adapted to form a shoulder to 85 prevent the shuttle 20 from leaving the surface of the member 15. Between the flanges 17 and 18 there is a raceway 21 for the shuttle 20 and the leather picker 22. The leather picker 22 is actuated forward, whereby to 90 throw the shuttle 20 across the loom by means of a movable slide 26 having a post 27 that projects up through the leather picker 22. The movable slide 26 is shouldered to fit into a correspondingly formed 95 recess in the lower side of the member 15 and is attached by a cord 28 to a lever 29 that is fulcrumed at 30 to the bracket 31 mounted to the cross bar 32 of the frame —1—. The cord 28 passes over the grooved 100 guide pulleys 32^a, 33 and 34 which revolve upon axles supported by the brackets 35, 36 and 37, respectively. The bracket 32 is attached to the member 15 and the brackets 36 and 37 to the cross bar 32. The lever 29 is provided with a nub 40 against which impinges once every revolution a roller 41 that is mounted to turn upon an axle fixed 105

to the arm 42. The arm 42 is held to revolve with the rock shaft 13 having bearings at either end in the cross bars 39-39 of the loom frame —1—. The impinging 5 of the roller 41 against the nub 40 of the lever 29 rocks said lever 29 downward upon its fulcrum and against the tension of the coiled spring 43 that is disposed between the lower surface of the lever 29 and the upper 10 surface of the cross bar 32 of the frame —1—. The leather picker 22 is actuated in the reverse direction to that of the pull of the cord 28 by a coiled spring 44 attached at one end to the lower surface of the movable slide 26 and at the other end to the member 15 adjacent its outer edge.

The end of the member 15 opposite the end 16 is reduced at 23 to allow for the vertical movement of the shuttle boxes 24 holding shuttles 20 each of which carries a different colored thread. Although the shuttle boxes 24 move in a vertical manner, as is well known in the construction of looms, they do not move horizontally. Each of the 25 boxes 24 is formed with a slot 45 in one side, through which projects the picker end 46 of an arm 47 that is adapted to move forward to throw the shuttle 20 across the loom in the well known manner. The opposite end 30 of the arm 47 is sleeved at 49 to ride along the guide rod 50 having bearings at one end in the sword 4 and at the other in the plate 51 attached by a bolt to the member 15. A cleat 52 provided with a recess 53 for the 35 movement of the arm 47 is disposed adjacent the member 15 and secured at one end to the sword 4 and at the other to the plate 51. Each of the boxes 24 has an opening at 48 adjacent the rear end, whereby the picker 46 of the arm 47 may pass from the slot 45 of the one box 24 to the other, when said boxes 40 24 are shifted in a vertical manner.

The arm 47 is provided with a recess up 45 through which projects a post 54 fixed to the movable slide 55. A cleat 56 having an elongated slot 57 is attached to the side of the member 15 and is secured at one end to the plate 51 and at the other to the enlarged part 58 of the sword 4. The slot 57 is 50 formed for the horizontal movement of the post 54. The movable slide 55 is shouldered and fits into a correspondingly formed recess in the lower portion of the member 15 and of the cleat 56, similar to the construction of 55 the end 16 of the member 15. The slide 55 has a bolt 60 to which bolt is attached a cord 28^a to connect said slide 55 to a lever 29^a fulcrumed to a bracket 31^a mounted to a cross bar 32^a of the frame —1—. The cord 28^a 60 passes over the grooved guide pulleys 61, 62 and 63 adapted to revolve upon the axles having bearings in the brackets 64, 65 and 66, respectively. The bracket 64 is fixed to the member 15 of the lay 2 and the brackets

65 and 66 are fixed to a cross bar 32^a of the frame —1—. The lever 29^a is provided with a nub 40^a against which impinges a roller 41^a that revolves on an axle carried by an arm 42^a. The arm 42^a is fixed to turn with the rock shaft 13. On each revolution 70 of the arm 42^a, the roller 41^a impinges against the nub 40^a to move the lever 29^a against the tension of a spring 43, whereby to exert a pull on the cord 28 to actuate the arm 47 and the shuttle 20 across the loom in 75 the well known manner.

In operation, the crank shaft 7 and the rock shaft 13 are revolved by means of the meshing gears 11 and 12 and the pulley 14 which is turned by any well known motive 80 power, not shown here. The crank shaft 7 will revolve faster than the shaft 13 because of the ratio of gear 11 to gear 12, gear 11 being smaller than gear 12. As the crank shaft 7 revolves, the lay 2 which 85 is connected thereto by the arms 10 will rock back and forth. Furthermore, the revolving of the shaft 13 will cause the rollers 41 and 41^a on the arms 42 and 42^a to alternately strike the nubs 40 and 40^a of the 90 levers 29 and 29^a and thereby depress said levers 29 and 29^a against the tension of the springs 43 and 43^a, whereby to effect a pull in each instance upon the respective cords 28 and 28^a. This alternate pull on each of the 95 cords 28 and 28^a will draw in turn the respective movable slides 26 and 55 outward against the tension of a coiled spring 44 and 44^a to cause the leather pickers 22 and 46 to throw alternately the shuttle 20 across 100 the loom in different directions, whereby to supply the woof thread to the fabric. The shuttle boxes 24 will be shifted vertically at the proper times to furnish a different shuttle 20 carrying a given colored thread.

Having thus described our invention what we claim as new and desire to secure by Letters Patent is:

1. In a shuttle action for looms, a lay supported by adjustable swords, a shuttle, pickers disposed at either end of said lay, movable slides, posts connecting said pickers with the movable slides, levers having nubs, cords connecting said slides with the levers having nubs, means for depressing said levers having nubs, whereby to actuate the pickers to throw the shuttle alternately in opposite directions across the lay, and springs connecting the movable slides with the lay, whereby to return the pickers to 115 original position.

2. In a shuttle action for looms, a lay, adjustable swords for supporting said lay, a shuttle, a picker disposed between flanges at one end of said lay, a picker formed on the 120 end of an arm disposed at the other end of said lay, a sleeve on said arm, a guide rod upon which said sleeve slides, T shaped mov-

able slides, posts connecting said pickers with the T shaped movable slides, levers having nubs, means connecting said T shaped movable slides with the levers having 5 nubs, and arms carrying rollers adapted to impinge against said nubs, whereby to rock the levers to actuate the pickers and thereby

throw the shuttle alternately in opposite directions across the lay.

In testimony whereof we have affixed our 10 signatures.

JOZEF WOJTASIEWICZ.

JOHN ZAJAC.
